T. R. ARDEN.
LIQUID PROJECTING APPARATUS.
APPLICATION FILED APR. 29, 1916.

Patented Apr. 24, 1917.

UNITED STATES PATENT OFFICE.

THOMAS RAYMOND ARDEN, OF BROOKLYN, NEW YORK, ASSIGNOR TO DAVID HEYMAN, OF BROOKLYN, NEW YORK, AND LOUIS YANKAUER, OF NEW YORK, N. Y.

LIQUID-PROJECTING APPARATUS.

1,223,655.

Specification of Letters Patent. Patented Apr. 24, 1917.

Application filed April 29, 1916. Serial No. 94,323.

To all whom it may concern:

Be it known that I, THOMAS RAYMOND ARDEN, a citizen of the United States of America, residing at Brooklyn, in the county of Kings and State of New York, have invented certain new and useful Improvements in Liquid-Projecting Apparatus, of which the following is a specification.

My invention relates to a liquid projecting instrument, of the type generally termed liquid pistol, or squirt gun.

The principal object of the invention is to provide a device of this kind which shall be capable of use after the manner of a repeating gun, that is one in which quantities of liquid may be ejected at intervals, such quantities being taken from a reservoir forming part of the device.

A further object of the invention is to provide an exceedingly simple construction in which I dispense with valves to control the emission of liquid, and provide in lieu thereof a special form of trigger operated cell which governs liquid ejection.

Another object of the invention is to eliminate all valve mechanism over the liquid reservoir, to admit air in compensation for the liquid withdrawn, and to substitute for such valve mechanism a special type of plug through which air may enter the reservoir.

Other objects of the invention, its advantages and detail construction, will be described in the following specification reference being had to the accompanying drawing, in which—

Figure 1 is a vertical sectional view of the device in a position of rest;

Fig. 2 is a similar view thereof in the position of liquid ejection;

Fig. 3 is a vertical sectional view of a portion of the barrel and appurtenant parts on an enlarged scale; and

Fig. 4 is a fragmentary sectional view of a portion of the stock or handle and the barrel.

Referring to the drawing by reference characters, 10 denotes the stock or handle which is hollow so as to provide the liquid reservoir 11. The handle may be of any desired shape, although the substantially rectangular form shown in the drawing is

best suited for the purpose of supplying adequate space for the reception of a sufficient amount of liquid 12.

55

In suitable relation to the stock 10 is the barrel 13 which is preferably formed as an integral part of the stock, the rear wall 13^a of the barrel being positioned approximately over the median vertical line of the stock 10. The barrel 13 is provided with an elongated slot 14, in its lower portion, to permit of reciprocation of the trigger 15.

The trigger 15 is rigid with a cell 16, slideable in the barrel 13. The rear wall of the cell is orificed as at 17, to allow for the passage of a stationary piston therethrough, and its front wall is provided with a very considerably constricted ejection nozzle 18. The cell is normally pressed toward the front of the barrel by a coiled spring 16^a.

Secured to the rear wall 13^a of the barrel is a curved tube 19 which extends into the stock 10 and terminates a short distance above the base 10^a of the stock. Near its upper curved end, the tube 19 has a collar 20 which abuts one face of the wall 13^a, and adjacent collar 20, the tube 19 projects beyond the wall 13^a and has its projecting end threaded to receive the correspondingly inferiorly threaded end of a hollow piston 21. The end of the piston 21 which engages the tube 19 is also exteriorly threaded to receive a nut 22 whereby the piston 21 and tube 19 are firmly held together in position on the wall 13^a. Interposed between the nut 22 and the wall 13^a is a washer 23 of any suitable material.

The opposite end of the hollow stationary piston 21 is exteriorly threaded and carries thereon oppositely cupped washers 24 and 25 which are held in position by disks or plates 26 and 27 engaging respectively the washers 24 and 25. The cupped faces of these washers make frictional contact with the interior surface of the cell 16.

Traversing the hollow piston 21, intermediate its ends, is a pin 28 to which is secured one end of a spiral spring 29, the other end of which engages the tail of a valve 30. 100 This valve is substantially mushroom shaped and the periphery of its head is fairly sharp and engages the outer face of the disk 27. This construction of valve 30

is adopted so as to minimize the danger of particles lodging between the valve 30 and the disk 27 and impeding the operation of the device.

5 The upper wall of the stock is provided with a suitable orifice to receive a plug 31. This plug has a central bore into which is placed fibrous material 32 of any suitable character, impregnated with oil. The top 10 of the plug is covered by a disk or plate 33 having therein a small opening 34. The construction of the plug is such that when withdrawn from the reservoir 11, liquid is 15 withdrawn from the reservoir 11, air to replace such liquid is sucked through the opening 34, the central bore in the plug, and into the reservoir 11. Owing to the fact that the fibrous material 32 is impregnated with oil, such fibrous material will exert no capillary attraction on the liquid 12 and will not draw the same out of the reservoir 11.

20 The device operates substantially in the following manner: First remove the plug 31, fill the reservoir 11 with liquid 12 up to about the level shown in Fig. 1, and then replace the plug 31. Before any operation of the device the parts are in the position shown in Fig. 1 and the cell 30 is filled with air. Upon retraction of the trigger 15 the cell 16, which is freely movable in relation to the fixed piston 21, is retracted within the barrel and the air contained in such cell is expelled through the restricted nozzle 18. During the retraction of the cell 16 the spring 16^a has been compressed. When the trigger 15 is released the spring 16^a expands and projects the cell in the barrel. As a result of this forward movement of the cell the internal capacity of the latter is increased tending to the development of sub-atmospheric pressure therein. This sub-atmospheric pressure results in unseating the valve 30 and drawing or sucking water from the reservoir 11 through the tube 19, stationary piston 21 and into the cell 16. The nozzle 18 is of such a restricted character as to 45 counteract any tendency to draw a substantial quantity of air into the cell 16 to break the vacuum therein. Then upon a second retraction of the cell 16 by means of the trigger 15 the water in the cell will be expelled in a fine stream through the nozzle 18 and the front opening 35 in the barrel. This operation is repeated as frequently as 50 the trigger is actuated and until the reservoir 11 has been emptied of water.

55 It is evident that the pistol may be discharged, "repeated" as often as there is liquid in the reservoir 11.

60 During each discharge of the pistol air will flow through the hollow plug 32 into the reservoir 11 to compensate for the quantity of liquid withdrawn from the latter.

65 The cupped washers 24 and 25 prevent any liquid which enters the forward part of

the cell 16 from finding its way to the rear part of such cell.

The front end of the barrel is provided with the inturned end or flange 13^a to limit the forward movement of the cell 16, under the action of the expanding compressed air.

What I claim as new and desire to secure by Letters Patent of the United States is:—

1. In a device of the character described, the combination of a liquid reservoir, a barrel, a piston in said barrel, a cell movable in said barrel, there being a passage providing communication between said reservoir and the interior of said cell, and a valve at one end of said passage for controlling the emission of liquid therefrom. 75

2. In a device of the character described, the combination of a stock having a liquid reservoir therein, a barrel carried by said stock, a movable cell in said barrel, and a valve-controlled piston adapted to place said cell in communication with the reservoir. 85

3. In a device of the character described, the combination of a stock having a liquid reservoir therein, a barrel carried by said stock, a movable cell in said barrel, a valve-controlled piston adapted to place said cell in communication with the reservoir, and a trigger for moving the cell in the barrel. 90

4. In a device of the character described, the combination of a stock having a liquid reservoir therein, a barrel carried by said stock, a hollow piston stationarily supported in said barrel, a tube extending through said reservoir into communication with said piston, a valve at the outlet end of said piston, and a cell reciprocable in said barrel and into which the valved end of said piston projects. 100

5. In a device of the character described, the combination of a stock having a liquid reservoir therein, a barrel carried by said stock, a hollow piston stationarily supported in said barrel, a tube extending through said reservoir into communication with said piston, a valve at the outlet end of said piston, a cell reciprocable in said barrel and into which the valved end of said piston projects, and washers on said piston making a frictional fit with the inner face of said cell. 110

6. In a device of the character described, the combination of a stock having a liquid reservoir therein, a barrel in communication with said reservoir, a cell reciprocable in said barrel and adapted to receive and eject limited quantities of liquid, and a plug adapted to close said reservoir, said plug having a bore therethrough containing fibrous material impregnated with a fatty substance. 120

7. In a device of the character described, the combination of a stock having a reservoir therein, a barrel carried by said stock and having its front end inturned to form a flange, a tube extending through said reservoir, 125

voir, a hollow piston stationarily supported in said barrel and communicating with said tube, a substantially mushroom shaped valve at the outlet end of said piston, a spring for normally seating said valve to close the outlet end of the piston, a cell slidable in said barrel and having an ejection nozzle at its front end, a trigger for operating said cell, and cupped washers on the piston and mak-

ing a friction fit with the inner face of the 10 cell.

In testimony whereof I have affixed my signature in presence of two witnesses.

THOMAS RAYMOND ARDEN.
